UNITED STATES PATENT OFFICE

93,089

DESIGN FOR A TRAY

Emile Bodé, Paris, France

Application June 16, 1934, Serial No. 52,200

Term of patent 14 years

To whom it may concern:

Be it known that I, EMILE BODÉ, a citizen of the Republic of France, residing at Paris, France, have invented a new, original, and ornamental Design for a Tray, of which the following is a specification, reference being had to the accompanying drawing, forming a part thereof.

In the drawing:

Fig. 1 is a perspective view of the tray.

Fig. 2 is a top plan view of the tray.

I claim:

The ornamental design for a tray, as shown.

EMILE BODÉ.
